(57) **ABSTRACT**

A new and distinct *Sansevieria* plant having grey leaves with stacked, dark green horizontal lines.

1 Drawing Sheet

1

Botanical classification: *Sansevieria sp.*

Varietal denomination: 'OSV Sans 001'.

BACKGROUND OF THE INVENTION

The present invention comprises a new and distinct variety of *Sansevieria* plant, having the varietal name of 'OSV Sans 001' and commercially referred to as "Silver Star". The new variety was discovered and selected by the breeder in a cultivated production bed environment in Williamsburg, Costa Rica as a naturally occurring mutation amongst a population of unpatented and unnamed *Sansevieria* plants. As such, the exact parentage is unknown. The new variety was selected and first asexually reproduced by rhizome cuttings in Williamsburg, Costa Rica. 'OSV Sans 001' has been trial and field tested and has been found to retain its distinctive characteristics and remain true to type through successive propagations. The present invention has not been evaluated under all possible environmental conditions. The phenotype may vary with variations in environment without a change in the genotype of the plant.

When compared to *Sansevieria* variety named 'OSV Sans 004' (U.S. Plant patent application Ser. No. 17/495,477), the new variety exhibits a similar rosette leaf formation with leaves growing upward and then curving outward and having a gladiate leaf shape. However, 'OSV Sans 001' differs from 'OSV Sans 004' in having distinct margins along the leaf edges and horizontally stacked, green static lines with no yellow-green colored center band across the leaves (the

2

static lines of 'OSV Sans 004' are whitish in color with a yellow-green colored center band). Further, the following characteristics distinguish 'OSV Sans 001' from other *Sansevieria* varieties known to the breeder:

- 5 Rosette leaf formation;
Produces pups (offspring plants) before fully rooted;
An average of three pups is produced per potted plant; and
Horizontally stacked and static lines are present across
leaves.

10 **DESCRIPTION OF THE DRAWING**

15 The accompanying photographic drawing taken at approximately 18 weeks of age illustrates the new variety, with the colors being as nearly true as is possible with color illustrations of this type.

DESCRIPTION OF THE PLANT

20 The following detailed description sets forth the characteristics of the new variety at approximately 2 years of age. The data which defines these characteristics was collected in a greenhouse in September of 2021 in Winter Garden, Fla. Plants of the new variety were grown under 2,000 foot candles of artificial light in 15 cm pots in a climate-controlled greenhouse in Winter Garden, Fla. having 86% relative humidity and an average temperature of 28° C. Color references are primarily to the Munsell Plant Tissue Color Book, 2019 publication, except where general color terms are used.

PLANT

Time to initiate roots: About 12 days at an average of 23° C. night temperatures and 30° C. day temperatures. Time to develop roots: About 21 days at an average of 23° C. night temperatures and 30° C. day temperatures. Time to produce a finished plant from a rooted cutting: About 8 weeks in a 15 cm container. Rooting habit and description: Roots spread out and wrap at the base and are white to orange in color. Form: Spreading. Height from media surface to top of foliage: 19.0 cm. Plant diameter: 22.9 cm. Plant shape: Rosette, having a circular arrangement of the leaves. Vigor: Strong. Strength: Rigid, with no need for artificial support. Disease resistance/susceptibility: Nothing specific noted to date. Pest resistance/susceptibility: Resistant to thrips and aphids. Temperature tolerance: Sensitive to temperatures below 7° C. or above 38° C. Drought tolerance: Very tolerant due to the ability of the leaves to retain water. Flowers: None observed to date. Seeds/fruit: None present. Stem:
Length.—2.5 cm.
Diameter.—1.9 cm.
Shape.—Vertical column.
Color.—2.5GY 8/2.
Texture.—Coriaceous and glabrous.
Strength.—Sturdy and rigid.
Internode length.—Not applicable.

Leaves:
Arrangement.—Basal rosette.
Average number per plant.—20.
Length.—16.5 cm.

Width.—7.0 cm.
Shape of leaf (generally).—Gladiate.
Shape of apex.—Apiculate.
Shape of base.—Cuneate.
Margin description.—Entire.
Aspect.—Mostly erect, arching outwardly to about 75°.
Texture and luster.—Upper surface: Coriaceous and glabrous. Lower surface: Coriaceous and glabrous.
Pubescence.—Upper surface: None present. Lower surface: None present.
Fragrance.—None present.
Color.—Young leaves: Upper surface: 5Y 8/8 to 2.5GY 8/2 margins; few, weak 5G 3/2 stacked horizontal lines with random and faded 7.5GY 7/2 lines present on a background of 2.5GY 6/2. Lower surface: Mostly 2.5G 3/2 margins with some 5Y 8/8 present; few, weak 5G 3/2 stacked horizontal lines with random 7.5GY 7/2 lines present on a background of 2.5GY 6/2 that fades into 7.5GY 6/6. Mature leaves: Upper surface: 2.5GY 8/2 thin margins; few, weak 5G 3/2 stacked horizontal lines with 7.5GY 7/2 vertical lines near margin present on a background of 7.5GY 4/4. Lower surface: 2.5GY 8/2 thin margins; few, weak 5G 3/2 stacked horizontal lines present on a background of 7.5GY 5/6.
Veins.—Venation pattern: Parallel. Color: Upper surface: 7.5GY 5/6 alternating with 5G 3/2. Lower surface: 7.5GY 5/6 alternating with 5G 3/2.
Sheath:
Length.—1.3 cm.
Width.—5.1 cm.
Color.—2.5GY 8/2.
Texture.—Coriaceous and glabrous.

The invention claimed is:
1. A new and distinct variety of *Sansevieria* plant named 'OSV Sans 001', as is herein illustrated and described.
